United States Patent Office.

DENNIS LADD, OF CHICAGO, ILLINOIS.

Letters Patent No. 99,093, dated January 25, 1870.

IMPROVEMENT IN GRAIN-SEPARATORS.

The Schedule referred to in these Letters Patent and making part of the same.

To whom it may concern:

Be it known that I, DENNIS LADD, of Chicago, in the county of Cook, and State of Illinois, have invented a new and useful Improvement in Grain-Separators; and I do declare that the following is a true and accurate description thereof, reference being had to the accompanying drawings, and to the letters of reference marked thereon, and being a part of this specification.

Figure 1 is a perspective view of my invention, broken off at parts to show its mechanism.

Figure 2 is a detached sectional view of the straw-carrier.

A represents the frame which supports all the apparatus.

B, the ordinary threshing-cylinder, is provided with the concave C, the whole being encased by the sides D.

E is a straw-carrier for conveying the straw from the cylinder after it has been cleaned, and is constructed of iron or other metal rods or wires, with the outer ends bent, forming a chain, as at F, so that they are connected, forming one continuous or endless chain, which derives motion from pulleys G, H, and J, connected by belt to the pulley on the outer end of cylinder shaft K.

Below and at the rear of cylinder B is placed fan L, which receives motion by belt from shaft K.

Below and under cylinder B is grate M, which extends to and on top of division-board N.

Hopper-bonnet O is firmly secured below grate M, with its lower end or mouth extending into the upper end of rotating screen P, and receives motion by means of the bevel-gear wheels 2, shaft 3, pulleys 4 and H.

Fluke-boards or air-guides are placed in front of the fan and back of the grate-bars M, and are secured in the desired position by the aid of pawls and ratchets 5.

The rotating cylinder or screen P is or may be covered with wired cloth of different sized meshes, the division being at S.

The receptacle-box T is suspended by rod U and yoke W to the frame A, and is provided with partition-board Y, and is so constructed that it may be tilted so as to discharge the grain on either side through the orifices 6.

Having named the various parts of my invention, I will now describe its operation.

The unthreshed grain and straw are fed into the machine over apron 7. The straw is retained upon the carrier after being threshed, and is carried back from the thresher by the action of said carrier when the machine is in motion, while the grain and chaff pass down, and are separated by the grate-bars.

The chaff passes out over the board N, while the grain passes on into and through the bonnet O into the screen P, where the grain passes through the meshes of the wire, and the refuse matter is thrown out at the lower end of the screen.

The above-mentioned flukes serve to elevate or depress the current of air, as may be desired. It is suggested that a brush be attached to the lower side of the division-board N, which will come in contact with the face of the screen, serving to keep it always clean. The whole thus forms a very convenient and compact machine for the purposes intended.

What I claim as my invention, and desire to secure by Letters Patent, is—

1. The construction and arrangement of the guide-board N, the grated bars M, the bonnet O, and revolving screw P, as above set forth, and for the purposes above specified.

2. In combination with the above, the carrier E, with its devices for rotation, and the tilting-box T, when constructed, arranged, and operating as and for the purposes aforesaid.

DENNIS LADD.
